SUPPORT FOR BATH

Normand Bolduc, 11048 Ethier St., Apt. 1,
Montreal North, Quebec, Canada

Filed Feb. 17, 1972, Ser. No. 227,313

Term of patent 14 years

Int. Cl. D8—08; D23—02

U.S. Cl. D23—70

FIG. 1 is a perspective view of the support for bath according to the new design,

FIG. 2 is a front elevational view thereof, and

FIG. 3 is a side view from the left end side of FIG. 2. The broken lines are for illustrative purposes only.

I claim:

The ornamental design for a support for bath, substantially as shown and described.
